(57) The ornamental design for a golf ball pickup device, as shown and described.

DESCRIPTION

FIG. 1 is a bottom-left-front perspective view of a golf ball pickup device, showing my new design;

FIG. 2 is a bottom-right-front perspective view thereof;

FIG. 3 is a bottom-left-rear perspective view thereof;

FIG. 4 is a bottom-right-rear perspective view thereof;

FIG. 5 is a top-left-front perspective view thereof;

FIG. 6 is a top-right-front perspective view thereof;

FIG. 7 is a front elevational view thereof;

FIG. 8 is a rear elevational view thereof;

FIG. 9 is a left-side elevational view thereof, a right-side elevational view being a mirror image thereof;

FIG. 10 is a top plan view thereof; and,

FIG. 11 is a bottom plan view thereof.

The evenly-broken dash-dot lines in the views illustrate portions of the golf ball pickup device that form no part of the claimed design. The broken dash-dot lines in the views define boundaries of the claimed design and form no part of the claimed design.
